SPRING MOUNTED MINE CAR

Herman H. Pancake, Berwick, Pa., assignor to
American Car and Foundry Company, New
York, N. Y., a corporation of New Jersey

Application April 20, 1940, Serial No. 330,667

9 Claims. (Cl. 105—364)

This invention relates to mine cars in general and in particular to metallic mine cars which are mounted on springs or other resilient members.

The bulk of mine cars in the past have been constructed wholly of wood or of a combination of wood and metal and accordingly the cars could be mounted directly on the axles without special provision to absorb shocks. In recent years the trend has been toward all metallic cars and toward larger capacity cars and it has become almost necessary for these cars to be mounted upon resilient supports. It is an object, therefore, of the present invention to provide an all metal mine car which is mounted on resilient members to absorb shocks from the road-bed.

A further object of the invention is the provision of a mine car with special side sill elements and a new and improved type of resilient journal box mounting.

A still further object of the invention is the provision of an all metal mine car which is resiliently mounted on its axles in such a manner as to permit the floor to be carried as low as possible with respect to the wheels.

These and other objects of the invention will be apparent to persons skilled in the art from a study of the following description and accompanying drawings, in which:

Figure 1 is a side elevational view of the improved mine car;

Fig. 2 is an end view of the car with one-half thereof in section and taken on line 2—2 of Figure 1;

Fig. 3 is an inverted plan view of the mine car;

Fig. 4 is a sectional view through the improved axle box and side sill taken substantially in the plane of the axle;

Fig. 5 is a sectional view similar to Fig. 4 but taken on a transverse plane through the resilient mounting member;

Fig. 6 is a side view of a portion of the car showing a slight modification of the mounting means;

Fig. 7 is a sectional view taken through the modified mounting means of Fig. 6;

Fig. 8 is a sectional view taken through the side sill of the car and showing in detail the form of the sill as used in Figs. 1 to 7 inclusive;

Fig. 9 is a sectional view similar to Fig. 8 but showing a slight modification thereof for riveted construction;

Fig. 10 is a sectional view similar to Fig. 8 showing a still further modification, and

Fig. 11 is a similar sectional view showing a still further modification of the sill and combining riveted and welded construction.

Referring now to the drawings in detail, it will be seen that the car is constructed with end walls 2 and side walls 4 joined thereto and all connected in any suitable manner to an under-frame member. As is customary, side stakes 6 are connected to the side sheets and to the side sill elements either directly, as indicated in Figs. 2 and 8, or by means of gussets. The underframe member, as clearly shown in Figs. 2, and 4 to 8 inclusive, is formed by a floor sheet 8 having the side edges flanged downwardly as at 10 for the full depth of the sill element. The lower edge of this floor sill forming flange is welded as at 12 to the outer edge of a horizontal leg 14 of a pressed angle member which has its vertical leg 16 directed upwardly and welded as at 18 to the under side of the floor sheet. In this manner a complete box section side sill is formed at each side of the car by the flanged floor sheet and by the angle pressing. As clearly shown in Fig. 3, the vertical wall 16 and horizontal flange 14 of the angle member extend continuously from end to end of the car. In other words, the true box section sills extend continuously from end to end of the car and are closed at their ends by box section end sills. Each box section end sill is formed by an angle plate having vertical leg 20, outwardly directed lower horizontal leg 22 welded to the lower edge of vertical plate 24, the upper edge of which is welded to the ends of the floor sheet. It is, of course, obvious that if desired the ends of the floor sheet may be flanged downwardly but in practice it will be found more economical to form the end sill as described. In order to suitably brace the car floor to prevent sagging and to prevent distortion of the side sills, cross members such as channels 26 are provided extending across the car between the vertical legs 16 of the sills and the webs of these channel members may extend through notches in the leg 16 in order that they may be welded 45 to the downturned flange of the floor, as clearly shown in Fig. 3. The same result may be obtained by welding bracing plates to the floor and downturned flange prior to the application of the angle pressing, thus obviating the necessity of notching the leg 16 and producing a cheaper and fully as strong a construction. Such bracing plates are used to stiffen the end sill as indicated at 28 in Fig. 3. In addition, the end sills are reinforced by channels 30 bent to V form and secured to the central portion of the sills and to

the vertical leg 16 of the side sills. The end sills and end sill bracing means are pierced and suitably formed to receive spring mounted couplings C, while the end sills adjacent their ends have welded or otherwise secured thereto suitable spring mounted bumpers B. It will be seen that a minimum of metal has been used since the floor forms part of the side sill elements of the car and the end sill is constructed with a minimum of material yet yielding a maximum strength in each case.

In order to obtain as low a car as possible spaced openings are cut in the horizontal leg 14 in order to receive springs S, the upper ends of which support the car through the medium of a sill stiffening member 34 welded to the floor and sill forming sheet inside the box section sill. The lower ends of the springs which project below the box section sill element rest upon ledge 36 of a journal box J. This journal box is formed with a central axle receiving opening 38 formed by a continuation of the spring supporting ledge and by vertical walls 40 joined to the ends of the spring receiving ledge. These walls 40 are spaced apart a sufficient distance as to receive the box section sill element therebetween and have their ends trued and adapted to cooperate with guides 42 welded to the sides of the sill forming elements. Thus widely spaced guides are provided for the journal boxes beyond the supporting springs which will accordingly give greater stability to the journal boxes. The sides 40 of the journal box are slotted as at 44 to receive a bolt or other anchor means 46 extending through the sill element between the springs and preventing separation of the journal box and sill, while permitting motion of the journal box toward the sill element against the spring resistance. It will thus be seen that the journal box and spring elements telescope with the side sills of the car giving a compact, efficient arrangement and permitting the car floor to be carried as low as possible while still remaining above the side sills. The journal boxes, as clearly shown in Figs. 2, 3 and 4, are supported on the ends of axles A which are in turn supported by wheels W which, in the present instance, are of the antifriction type, that is, mounted on the axles through the medium of antifriction bearings.

In some rare instances it may be desirable to mount the car directly on the journal box without the use of springs and this may be readily accomplished as shown in Figs. 6 and 7 by interposing short lengths of pipe 50 within the box section sills and through which pipe bolts 52 may be passed to securely fasten journal box 54 directly onto the sill, thus the box section sill will be strengthened and crushing prevented by the use of the pipe which also acts as the positioning means for the bolts and which prevents the sill from being crushed by excessive tightening of the bolts.

In some instances it may be desirable to eliminate the welding and make the sill element of riveted construction and this may be accomplished as shown in Fig. 9. In this form the floor forming sheet is flanged upwardly as at 60 and directly connected by means, such as rivets 62, to the upwardly extending edge of a U-form sill element having outer leg 64, horizontal web 66 and vertical inner leg 67 terminating in an inwardly directed flange 68 riveted as at 69 to the floor sheet.

The sill element may also be formed, as clearly

shown in Fig. 10, by causing the floor sheet to be flanged upwardly as at 70 providing the side wall of the car, with the sill element formed by a true U-shaped member having outer and inner legs 72 and 74 respectively welded at their free edges to the floor and joined together by web 76 located in spaced relation to the floor.

The sill element may also be formed, as clearly shown in Fig. 11, by flanging the sides of the floor sheet downwardly as at 80, thence outwardly as at 82 with the free edge welded as at 83 to the lower free edge of an angle member. This angle member, as clearly shown, has the outer vertical leg 84 directed downwardly and the horizontal leg 86 directed inwardly and riveted or otherwise secured as at 87 to the floor forming sheet.

Regardless of the manner in which the box section sills are formed, the journal box mountings, shown in detail in Figs. 4 to 7 inclusive, may be used and accordingly details of the mounting on the specific forms of side sills have not been shown. It will be obvious, of course, that slight modifications in the journal box and journal box mountings will also be possible and while the invention has been described more or less in detail, it is to be understood that all such modifications and rearrangements of parts are contemplated as will fall within the scope of the appended claims defining my invention.

What is claimed is:

1. In a mine car, a body, spaced end sills, substantially closed box-section side sills extending from end sill to end sill and supporting the body and being formed in part by the floor of said body, axles extending transversely of the body wholly beneath the horizontal plane through the lowermost portion of said closed box section side sills and being supported on wheels, journal boxes supported on the axles and having parts thereof overlapping the outside side portions of said box-section side sills, and resilient means positioned within said box-section sills and resiliently supporting said body upon said journal boxes.

2. In a mine car, a body, spaced end sills, substantially closed box-section side sills extending from end sill to end sill and supporting the body and being formed in part by the floor of said body, axles extending transversely of the body wholly beneath the horizontal plane through the lowermost portion of said closed box section side sills and being supported on wheels, journal boxes supported on the axles and having upstanding outside side walls overlapping and guided by the side portions of said box-section side sills, and resilient means positioned within said box-section sills and resiliently supporting said body upon said journal boxes.

3. In a mine car, a body, spaced end sills, substantially closed box-section side sills extending from end sill to end sill and supporting the body and being formed in part by the floor of said body, axles extending transversely of the body wholly beneath the horizontal plane through the lowermost portion of said closed box section side sills and being supported on wheels, journal boxes supported on the axles and having spaced upstanding side walls, said side walls being of substantially the same height as said side sills and overlapping the outside side portions thereof, and resilient means positioned within said box-section sills and resiliently supporting said body upon said journal boxes.

4. In a mine car, a body, substantially closed box-section side sills supporting the body and be-

ing formed in part by said body, axles extending transversely of the body and being supported on wheels, journal boxes supported on the axles and having upstanding side walls of substantially the same height as the side sills, said side walls overlapping and being guided by the outside side portions of the sills, retaining means extending through said walls and sills and retaining said walls and sills against spreading and in overlapping relation, and resilient means positioned within said box-section sills on either side of said retaining means and resiliently supporting said body upon the journal boxes.

5. In a mine car, a body, substantially closed box-section side sills supporting the body and being formed in part by said body, axles extending transversely of the body and being supported on wheels, journal boxes supported on the axles and having spaced upstanding side walls overlapping the outer sides of the side portions of said box-section sills, means secured at spaced points to the outer sides of the side portions of said sills and slidably engaging the ends of said spaced upstanding side walls to limit the same to substantially vertical movements, and resilient means positioned within said box-section sills and resiliently supporting said body upon the journal boxes.

6. In a mine car, a body, substantially closed box-section side sills supporting the body, axles extending transversely of the body and supported on wheels, journal boxes supported on the axles and having spaced upstanding side walls guided by the outside side portions of the side sills, and spring means located partially within said closed box section side sills and extending below the same into bearing engagement with said journal boxes to resiliently support the body on the journal boxes.

7. In a mine car, a body, substantially closed box-section side sills supporting the body, axles

extending transversely of the body and supported on wheels, journal boxes supported on the axles and having spaced upstanding side walls guided by the side portions of the side sills, means secured to the outer side of the closed box section side sills and cooperating with said upstanding side walls to limit longitudinal movement of said journal box, and springs located within the side sills and bearing on said journal boxes to resiliently support the body on the journal boxes.

8. In a mine car, a body, substantially closed box-section side sills supporting the body and being formed in part by said body, axles extending transversely of the body and being supported on wheels, journal boxes supported on the axles and having spaced upstanding side walls overlapping the outer sides of the side portions of said box section sills, means secured to the outer sides of the closed box-section side sills and providing guide surfaces cooperating with the end edges of said upstanding journal box side walls to limit longitudinal movement thereof, and resilient means located within the side sills and bearing on said journal boxes to resiliently support the body thereon.

9. In a mine car, a body, substantially closed box-section side sills supporting the body, axles extending transversely of the body and supported on wheels, journal boxes supported on the axles and having spaced upstanding side walls guided by the side portions of the side sills, means secured to the outer sides of the closed box-section side sills and providing guide surfaces cooperating with the end edges of said upstanding side walls of the journal boxes to limit longitudinal movement thereof, and resilient means located within the side sills and between planes extending transversely of the sill through the guide surfaces, said resilient means bearing on said journal boxes to resiliently support the body thereon.

HERMAN H. PANCAKE.
